(57) **CLAIM**

The ornamental design for stretching exercise equipment as shown and described.

DESCRIPTION

FIG. 1 is a perspective view of a stretching exercise equipment;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is an enlarged view of the handle portions thereof. The dot dash lines are for the purpose of showing the enlarged portions and form no part of the claimed design.
